APPARATUS FOR STRAINING LIQUIDS
OR GASES

John Wardle, Westminster, London, England, assignor to Lelos Strainers Limited, Barrow-in-Furness, England, a British company

Original application July 9, 1932, Serial No. 621,600. Divided and this application July 1, 1933, Serial No. 678,690. In Great Britain October 14, 1931

6 Claims. (Cl. 210—167)

This invention relates to apparatus for straining liquids or gases and its chief object is to provide a mechanical cleaning device for the straining medium.

5 In order that the said invention may be clearly understood and readily carried into effect the same will now be described with reference to the accompanying diagrammatic drawing and will be defined in the appended claims.

10 In the drawing:—

Figure 1 is a central vertical section of one form of strainer provided with a cleaning device in accordance with this invention;

15 Figure 2 is an enlarged view of part of the cleaning device shown in Figure 1;

Figure 3 is a section on line II—II on Figure 1; and

20 Figure 4 is a section illustrating a modification in which the cleaning elements are located within the strainer body.

In Figures 1, 2, and 3, the strainer body A is formed peripherally with longitudinally disposed ribs a around which the wire A¹ is wound spirally, and with longitudinal slits, grooves, or the like, 25 (not shown) for the passage of the liquids or gases. The cleaning device comprises toothed or notched discs X that engage between the convolutions of the wire A¹ and gear with the ribs a. The discs X are carried by a spindle X¹. The 30 discs X may be formed as independent elements and spaced apart by distance pieces X² or they may be formed integrally with each other and with the distance pieces X² (and with the spindle X¹ also if desired) by forming a toothed cylinder and cutting slots in the teeth for the reception of the convolutions of wire. The spindle X¹ is mounted in the casing E so as to be capable 35 of axial sliding movement or the discs or cylinder may be axially slidable on the spindle X¹. The strainer body A and cleaning device are located 40 within the casing E which has an inlet opening E⁴, outlet opening E¹, and a sump E². The strainer body A is journaled at A²¹, A²², in the casing E and at A²¹ is provided with apertures A²³, through 45 which the liquid or gas from the inlet E⁴ enters into the interior of the strainer body A and passes between the convolutions of wire A¹ to the outlet E¹. The strainer body A is also provided with a spindle A²⁴ that extends through an aperture in 50 the upper wall of the casing E and has a handle A²⁵ on its outer end. Rotation of handle A²⁵ causes the strainer body A and cleaning device to rotate so that any foreign matter located between the convolutions of wire is dislodged into the interior of the body A whence it falls into the sump 55

E² from which it can be removed after detaching a screw plug E³. During such rotation the convolutions of wire cause the discs X or spindle X¹ to move axially.

Figure 4 illustrates a modification in which the 5 cleaning elements or discs X are mounted within the strainer body the teeth a of which latter are accordingly formed of increasing cross-sectional area towards their outermost surfaces, the teeth on the discs X also being suitably shaped. In this 10 arrangement the gas or liquid will pass between the convolutions of wire A¹ from the outside to the interior of the strainer body and the dirt will be pressed by the discs X to the outside of the strainer body when the latter and the discs X are 15 rotated.

What I claim and desire to secure by Letters Patent of the United States is:—

1. Apparatus for straining fluid comprising a cylindrical strainer body provided with passages 20 for the fluid, and having a helical groove on its outer surface, a straining medium consisting of a wire wound in said helical groove, and mechanical cleaning devices provided with teeth which pass between adjacent convolutions of 25 the wire and which enter said passages thereby gearing with said body.

2. Apparatus for straining fluid comprising a rotatably mounted cylindrical strainer body provided with longitudinal openings for the fluid 30 and with a helical groove on its outer surface, a straining medium consisting of a wire wound in the said helical groove, a spindle parallel to but offset from the axis of the cylindrical strainer body, and toothed cleaning devices mounted on 35 said spindle and provided with teeth which pass between adjacent convolutions of the wire and enter said openings thereby gearing with said strainer body.

3. Apparatus as in claim 2, wherein said spindle 40 is mounted within the strainer body and means are provided whereby the normal flow of fluid occurs from outside the strainer body through the straining medium into the interior of the strainer body.

4. Apparatus as in claim 2 wherein said spindle is mounted outside the strainer body and means are provided whereby the normal flow of fluid occurs from the interior of the strainer body through the straining medium to the exterior of 50 the strainer body.

5. Apparatus as in claim 1 wherein the cleaning devices comprise integral projections of a slotted and toothed cylinder.

6. Apparatus for straining fluid comprising a 55

cylindrical strainer cage provided with a surrounding helical groove and provided with a straining medium including a wire wound in said groove forming fluid passages opening to the cage interior between adjacent convolutions of the wire, mechanical cleaning means provided with teeth entering passages between the wire

convolutions and means for rotating said cage and straining medium and thereby causing circumferential movement of said cage and straining medium with respect to the cleaning means and axial movement of the cleaning means with respect to the cage and straining medium. ⁵

JOHN WARDLE.
